UNITED STATES PATENT OFFICE.

JOHN A. DAVIS, OF SPRINGFIELD, OHIO.

DESIGN FOR A CHAMBER-VESSEL.

SPECIFICATION forming part of Design No. 18,260, dated April 17, 1888.

Application filed March 1, 1888. Serial No. 265,866. Term of patent 7 years.

To all whom it may concern:

Be it known that I, JOHN A. DAVIS, a citizen of the United States, residing at Springfield, in the county of Clark and State of Ohio, 5 have invented and produced a new and original Design for Chamber-Vessels, of which the following is a specification, reference being had to the accompanying drawings, and to the letters and figures of reference marked thereon, 10 which form a part of this specification.

Figure 1 is a top view of a chamber-vessel embodying my design. Fig. 2 is a vertical section of a chamber vessel, showing that part embracing my design in elevation. Fig. 3 is 15 a cross-section of the beaded edge *a* on lines 1, 2, Figs. 1, 2.

The leading feature of my design consists in the form of the top or free edge of the diaphragm. This is formed with a downward 20 curve from where its respective ends are joined to the wall of the chamber-vessel toward the middle part, so that the latter shall be the lowest part of said free edge.

A is the chamber-vessel, which is circular in

its general contour. *B* is the diaphragm of 25 the same. This latter has a round or beaded top edge, *a*, curved in contour from where its ends join the wall of the vessel *A*, just below the top, toward the middle part, so that when viewed in elevation the middle portion of the 30 edge *a* is the lowest, and its contour is nearly that of a section of a circle. This form of the edge *a* can be made irrespective of the shape of the inclined surface of the diaphragm, which may be concave, concavo convex, or flat without materially departing from my invention.

I claim—

The design herein shown and specified, consisting of the chamber-vessel *A*, having a diaphragm, *B*, formed with the middle portion of 40 its top edge, *a*, lower than the ends.

In testimony whereof I affix my signature in presence of two witnesses.

JOHN A. DAVIS.

Witnesses:

B. C. CONVERSE,
FLETCHER WHITE.
